SANDING MACHINE

Application filed July 12, 1930. Serial No. 467,418.

This invention relates to a sanding roll.

The chief object of the invention is to produce a sanding roll which will be truly cylindrical in cross section, whereby flats and other deformations heretofore obtained in sanding rolls are eliminated.

The chief feature of the invention consists in the accomplishment of the foregoing object by the formation of an endless tubular sanding surface and the mounting thereof upon a supporting cylinder for forming a truly cylindrical roll.

Another feature of the invention consists in the formation of the cylindrical support in such a manner that the tubular endless sanding surface may be readily mounted upon a portion of the cylindrical support and thereafter positioned in truly cylindrical form and supported therein by the remainder of the cylindrical support forming parts.

A further feature of the invention consists in the automatic locking together of the relatively movable parts constituting the cylindrical support.

The full nature of the invention will be understood from the accompanying drawings and the following description and claims:

In the drawings Fig. 1 illustrates in elevation a sanding machine with parts shown in longitudinal section to illustrate the same in detail. Fig. 2 is an axial sectional view through the roll and its supports. Fig. 3 is a transverse sectional view taken on line 3—3 of Fig. 2 and in the direction of the arrows and of the roll in its completed form. Fig. 4 is a view similar to Fig. 3 but with the roll in incomplete formation showing one step in the formation of the roll. Fig. 5 is a top plan view of the roll support with the sanding surface and intermediate supporting medium removed. Fig. 6 is a perspective view of the endless tubular sanding surface. Fig. 7 is a perspective view of one of the detachable segments.

In Fig. 1 there is conventionally illustrated a power sanding machine including the side frames 10, a table or work supporting element 11 and a power source or motor 12 which through the endless belts 13, 14 and 15 feeds the work 16 through the machine

through the medium of the feeding rolls 17, and sands said work through the medium of the sanding rolls 18. Intermediate driving connections 19 are associated with the belt 15 and the feeding rolls 17. Idler rolls 20 are associated with the sanding rolls 18 and the endless driving belt 14.

Heretofore the sanding rolls which may be employed in machines of the aforesaid character, or in any other suitable machine, comprised parted or split substantially cylindrical rolls over which a sheet of sand paper or the like was laid, having two free ends clamped in place. When the same was locked together the sanding surface was thereby anchored to the supporting roll. However, such a construction was not truly cylindrical and therefore flats were developed which left undesirable waves on the sanded surface.

The present invention employs a truly cylindrical roll which maintains a uniform sanding action and does not produce waves in the work when sanded. The invention consists in the provision of an endless tubular sand paper or the like formed by suitable lapping or splicing or otherwise securing of the two adjacent edges thereof into tubular formation with the joint 22 of an indistinguishable character, reference being had not to observation of the joint but to the effect of said joint upon the work when sanded thereby.

The sanding cylinder for supporting the tubular sanding surface 21 comprises a recessed cylinder 23 having the stub shafts 24, which is provided with a plurality of longitudinally extending undercut recesses 25 equally spaced about its periphery, there being shown herein three of such recesses. The recesses are tapered from one end to the other while being of constant depth from end to end. The cylindrical surface portions 26 of the recessed cylinder are only maintained intermediate the grooves 25 for the length thereof. As shown in Fig. 4, the grooves are undercut as indicated at 27 so as to coact with the segments mounted therein for retaining them in interlocking position against displacement by the centrifugal force due to rotary movement of the cylinder. Slidably

mounted in each of the recesses 25 there is a segment 29 so formed as to be slidable therein from the enlarged end and fit snugly in wedging position. Corresponding with the 5 formation of the recesses, the segments are tapered from end to end, having the sides 31 thereof extending outwardly to conform and interlock with the undercut sides 27 of the grooves 25.

10 Thus after the tubular sand paper has been mounted over the roll as will be hereinafter described and the segments 29 are mounted in position, they will be locked in place by the dove-tail undercut formation against dis- 15 placement by centrifugal force, and will be held by the wedging action against dislodg- 20 ment longitudinally.

In the present invention there is also em- 25 ployed an endless tubular cushion support 33 which is of felt material. The formation of the truly cylindrical sanding roll is as fol- 30 lows: The endless tubular felt or cushion is positioned within the endless tubular sand- 35 ing surface or sand paper roll and the same then are telescopically mounted over the cyl- 40 inder 23. This is shown in Fig. 4 and it will be noted from said figure that the portions which are positioned immediately opposite the groove and cover the same extend chord- 45 like directly across the groove. After thus positioning the sand paper tube, the several segments 29 are inserted in the mouth of the grooves 25 and are driven home.

It will be understood that there is no sub- 50 stantial stretching or expansion of the end- 55 less tubular felt or sand paper, for the cyl- 60 inder supporting surface is constant and uni- 65 form, all of the wedging being in other direc- 70 tions. The mounting of the segments accom- 75 plishes the elimination of slack in the sand- 80 paper tube and forms it into truly cylindrical form.

If desired, clamping rings 34 having the clamping ears 35 and clamping means 36, in- 85 cluding bolt and nut, may be associated with the ends of the rolls to prevent longitudinal 90 relative movement.

One of the stub shafts 24 is extended and carries a driving pulley driven by the belt 95 14. Said shaft is detachable from the pulley by the axial relative movement therebetween, and a guide or support 37 supports ball bearings 38 which rotatably support the shaft 24. The opposite end of the roller through the 100 145 stub shaft 24 is associated with the ball bearings 39, the same being receivable by a recess 40 formed in an arm 41 constituting a shaft support. Said arm 41 is longitudinally movable with respect to the roll for roll demount- 105 150 ing. Herein such possible movement is shown by the shaft support 41 being hingedly supported at 42 and being locked in shaft supporting position by suitable means 43. When the lock or retainer 43 is disconnected, 110 155 the shaft support 41 may be tilted and the

roll removed longitudinally for renewing the sand paper.

The invention claimed is:

1. A sanding roll comprising a rotary drum having longitudinal grooves formed in the periphery thereof, an endless cylindrical sanding tube removably mounted thereover, means for rotating said drum, and segmental members adapted to be mounted in said grooves and having a surface conforming with the surface of said drum in order to permit a loose mounting of the sanding tube on the drum and the completion of the mounting by insertion of the segments to provide uniform support under the 70 75 entire cylindrical surface of the sanding tube.

2. In a sanding roll, the combination with an endless cylindrical sanding tube, of a support therefor comprising a drum having a 80 85 plurality of longitudinal grooves extending from end to end thereof for permitting said tube to be readily mounted thereover, and a plurality of segmental members adapted to slide into said grooves from one end thereof and having their exposed surfaces conforming to the cylindrical surface of said drum for filling out said tube and supporting the same uniformly under the entire surface 90 95 thereof.

3. In a sanding roll, the combination with an endless cylindrical sanding tube, of a support therefor comprising a drum having a plurality of grooves formed therein ex- 100 105 tending and tapered from one end to the other over which said tube is adapted to be mounted so as to extend chord-like across said grooves engaging the arcuate cylindri- 110 115 cal surfaces thereof, and a plurality of seg- 120 125 mental members tapering from one end to the other adapted to be mounted in said grooves from one end thereof so as to wedge against the sides thereof, the exposed surfaces of said segmental members conforming with the surface of said drum for providing a continuous cylindrical surface thereabout for supporting said tube in sanding position.

4. In a sanding roll, the combination with an endless cylindrical sanding tube, of a 115 120 support therefor comprising a drum having a plurality of longitudinally extending grooves formed in the surface thereof, said grooves having their sides undercut, and a plurality of segmental members adapted to be slidably mounted in said grooves from one end thereof after said tube has been mounted thereon, said members having their side surfaces so formed as to dove-tail in said grooves and interlock therewith and their exposed 125 130 surfaces conforming to the surface of said drum so as to provide a cylindrical periphery therefor for supporting said tube.

5. A sanding roll comprising a cylindri- 130 135 cal sanding tube and a rotary support there-

for, said support comprising a tubular cushion positioned within the sanding tube and a massive driving drum within the cushion, said driving drum having a hub portion and a plurality of rigidly connected spokes which flare outwardly from the hub to provide portions of a cylindrical surface on which the cushion and belt may be loosely fitted, said rotary support being also provided with complementary locking members which have a taper fit between the spokes and which have outer areas complementary to the outer areas of the spokes, whereby the locking members may be introduced between the spokes and the cushion to provide along with the spokes complete cylindrical support under the cushion and sanding belt.
